(57) **CLAIM**

The ornamental design for an automotive component, as shown and described.

DESCRIPTION

FIG. 1 is a front perspective view of the automotive component of the present invention;

FIG. 2 is a rear perspective view thereof;

FIG. 3 is a front view thereof;

FIG. 4 is a rear view thereof;

FIG. 5 is a right side view thereof;

FIG. 6 is a left side view thereof; and,

FIG. 7 is a top view thereof.

The portions of the automotive component illustrated in broken lines form no part of the claimed subject matter.
